WICKET

Harry Sklar, New York, N. Y.

Application August 4, 1932, Serial No. 627,515

16 Claims. (Cl. 20—39)

This invention relates to wickets.

The invention is particularly directed to a wicket for association with a door of a dwelling, by means of which one within the dwelling may, without opening that door, determine who may have presented himself for admission to the dwelling and, if he so desires, may converse with that person without necessarily admitting him. In structure of this character, it is an object of the invention to arrange at the opening through the door, a closure which may be moved to uncover the entire opening, but itself having formed therethrough an opening or a peep-hole of sufficiently small extent that the party within the dwelling will be enabled to observe a person outside the door, without endangering himself, or being discovered in his observation.

It is an object of the invention to provide a wicket of the type indicated, in which the closure for the main door opening, when not sustained in open position by the hand of one immediately at the opening and within the dwelling, will gravitate automatically to closed position, and immediately thereupon latch positively in that position. When so latched, no pressure against the closure from the outside will suffice to disturb the latch, nor will shocks have any such effect.

For that purpose, the latch is comprised in a slide finger, retained within a recess in the closure, or otherwise disposed for free sliding movement. When the closure moves to its lowermost position, this latch falls into engagement with an abutment, preventing return of the closure until a force is applied to the latch by means of a suitably disposed button. Just before the latch seats in engagement with the abutment, and continuously during such engagement, the closure itself is engaged within a slot in the abutment to prevent opening movement of the closure other than in the plane of the closure.

A pair of recesses are formed in the closure, one at each face thereof. One of the recesses opens to be apparent through the opening in the door; characters arranged on the outer face of the closure will be apparent through that opening. Within that recess may be seated and retained metallic tablets carrying embossed characters indicating the desired information as to the apartment or the like with which the door is associated.

The other recess is shouldered to support a closure plate, forming a pocket in which is received a latch. A rivet pin, which retains the closure plate seated upon the shoulder, also acts as a guide and stop for the latch. This guide

cooperates with a slot in the closure plate in which a pin shank is engaged. The pin shank is attached directly to the latch and carries at its outer end a button by which the latch may be manipulated when releasing its engagement with the abutment and for swivelling the plate to reveal the opening.

By the arrangement of the two recesses, the closure is made of sufficient thickness for desired strength but, at the same time, the character carrying tablets are made capable of easy association and the latching mechanism assembled by a single, simple operation. All of this is effected without the sacrifice of neatness of construction and, in fact, with a material reduction of the total overall dimensions of the unit. By reason of the small space occupied by the latch, it is possible to dispose it on that portion of the closure which assumes the lowermost position when the closure has moved to latched position.

Other objects of this invention will hereinafter be set forth, or will be apparent from the description and the drawing, in which is illustrated an embodiment of apparatus carrying out the invention.

The invention, however, is not intended to be restricted to any particular construction or arrangement of parts, or to any particular application of such construction, or to any specific manner of use, or to any of the various details thereof, herein shown and described, as the same may be modified in various particulars or be applied in many varied relations without departing from the spirit and scope of the claimed invention, the practical embodiments herein illustrated and described merely showing one of the various forms and modifications in which the invention might be embodied.

On the drawing, in which the same reference characters refer to the same parts throughout, and in which is disclosed a preferred embodiment;

Fig. 1 is a vertical sectional view through a door, illustrating the arrangement thereon of a wicket embodying the invention;

Fig. 2 is a rear elevational view of the wicket, the closure being shown partially open to illustrate certain details of the closure construction and of the frame, the latching mechanism for the closure being shown in dotted lines in the position it assumes when the closure is moved to full opening covering position;

Fig. 3 is a detail elevational view of one element of the wicket;

Fig. 4 is a vertical sectional view, on the line 55

4—4 of Fig. 2, illustrating the construction of the inner portions of the wicket, and, in detail, of the latching mechanism;

5 Fig. 5 is an elevational view, illustrating the construction of the abutment and cam member with which the latch and the closure engage;

6 Fig. 6 is a detail sectional view, on the line 6—6 of Fig. 2, illustrating the construction of the pivot for the closure plate; and

10 Fig. 7 is a detail sectional view in the position of line 7—7 of Fig. 2, illustrating the construction of the assembly of the screws and related elements retaining the wicket assembled.

15 In the specific embodiment of the invention shown on the drawing, a wicket 10 is shown arranged in association with a door 12 through which an opening 14 has been provided for inspection of persons presenting themselves at the outside face, and through which conversation 20 with such persons may be had.

If desired, the wicket may include an ornamental frame 16 for the outer end of the opening. An extending escutcheon 18 may be formed with the frame, being provided with a recessed area 25 20 through which an opening 22 is cut. Name cards, retained between the escutcheon and the door and retained within the recess, are thus made clearly decipherable to one outside the door.

30 The frame preferably is retained upon the outer face of the door relatively to opening 14 by any suitable securing means; preferably, however, its mounting is assured in the manner to be indicated. The frame includes a flange 35 24 carrying suitable ornamentation on its outer face, and abutting against the door with its inner face. The frame also includes an annular ring 26 positioned within the opening in which it fits substantially snugly, thus functioning to 40 locate the frame positively in position. A pair of bosses 28 may be erected from the inner face of flange 24. When drilled, tapped and threaded, these bosses provide means for the reception of screws 30. The screws and their associated 45 bosses, for this purpose, extend through suitable openings through the door, separately made for that purpose and distinct from opening 14, or constructed as lateral extensions of opening 14. In this manner, the frame is retained against 50 rotation, while the outer ends of the screws, seated in the bosses, are not visible or accessible to one outside the dwelling.

55 The screw heads may be retained by the door; preferably, however, they serve to retain in associated relationship to opening 14 and frame 16, an annular plate 32. Face 34 of plate 32 preferably is flat, having a pair of recesses 36 formed therein for the reception of bosses 28 when the wicket is to be mounted on doors of 60 thin material. The other face of the plate is formed by a bevelled portion 38, leading up to a slight rise 40, which locates the substantially smooth, inner face 42 of the plate. Through the plate are provided passages 44 through which 65 screws 30 are extended, and countersunk to receive the heads of screws 30. Then, when the wicket is completely assembled, face 42 will be completely smooth except for a boss 46, projection 48 and recess 50, all to be described herein- 70 after.

75 Just off the vertical axis and on face 42 of plate 32 is formed boss 46. A closure plate 52, preferably circular in its general contour to conform with the preferred shaping of the opening and other portions of the wicket, has a bearing

ing portion 54 formed adjacent its edge and in a position such that, in its final mounting, the pivot to be formed by this bearing portion will be located just off the vertical gravitational axis of the closure plate. In other words, the plate, in its operation, will always have a force tending to rotate it about the axis of the bearing. Through the bearing portion is formed an opening 56 which is to be seated over boss 46, and the opposed faces of the plates brought into contact. When so assembled, the top of the boss is of substantially the same height as, or slightly higher than, flat face 58 of bearing portion 54.

10 Boss 46 has a passage 60 for the reception of a pin 62, the head 64 of which, in the final assembly, will abut face 58. The inner end of the pin may be swaged or riveted over within the countersunk portion 66 of passage 60. By this means, the plate is mounted for free pivoting movement on the boss which provides it a 20 bearing without subjecting it to the frictional drag of pin 62. The closure plate is of such dimensions that it will cover, in opening covering position, substantially the entire inner face 42, thus concealing, when in that position, the heads 25 of screws 30, as seen in Figs. 2 and 7.

Face 68 of closure plate 52, directed toward face 42, preferably is smooth to permit free sliding movement of the closure relative to the plate. However, the central portion of this face is depressed, providing a surface 70, guarded from contact with face 42 by this spacing. This surface may be ornamented in any desired manner. A recess 72, located centrally of the depressed surface, provides means for receiving metallic 35 tablets 74 upon which characters 76, imprinted thereon as by embossing, may be displayed to permit inspection through opening 14 for determining the particular room, apartment or the like to which the door gives access. The metal 40 at the edges of recess 72 may be swaged over to retain the tablets in position.

Closure plate 52 may be formed with a flange 78 of suitable thickness bounding its edge. A recess 80 is formed in the plate so that its bottom is substantially on the same level as the face of flange 78. Recesses 72 and 80, as described, open at opposite faces of the closure plate. They are dimensioned so that their walls come into 50 close proximity, as seen in Fig. 4, and yet leave sufficient metal for the requisite strength. This is of importance since the closure plate preferably is made by die-casting.

55 Recess 80 is located beyond the gravitational axis in which the pivot of bearing portion 54 and pin 62 lies. It will be apparent from the following that, under all circumstances, the latching mechanism 82, housed within the recess and co-operating with projection 48, will prevent movement of plate 52 to a position in which gravity 60 will not continue effective in its tendency to rotate the plate.

65 Recess 80 is formed with a shoulder 84. Upon this shoulder is intended to be seated a plate 86 to define a pocket for receiving a finger 88. The dimensions of finger and pocket are such that the finger is permitted free sliding movement. Plate 86 is retained fixedly related to the shoulder and the recess by the passage through an opening 90 70 in the plate of a pin 92. The pin, preferably formed integral with plate 52 and extending upwardly within the recess, is headed over in the manner of a rivet to retain these parts firmly associated. Pin 92 also passes through a slot 94 75

in finger 88 and thus retains the finger against separation from the closure.

At the lower edge of plate 32 there is erected projection 48, located, although not necessarily, on the vertical axis of the plate. In this case, the projection is provided with a cam surface 96 and a groove 98, the latter being cut parallel to the direction of swing, and in the plane, of the closure. The groove is made of a width just sufficient to receive flange 78. The projection might, if desired, be made large enough for a groove to receive the entire width of the closure. Preferably, for the purpose of this invention, flange 78 should be as thin as the element of strength will permit, in order that, with the assembly of the latching mechanism with the closure and the association of projection 48 with plate 32, the apparatus created will not be of undesirable bulk. A portion of flange 78 is cut away to form a straight edge 100 and a shoulder 102. When the plate rides into opening covering position, flange 78 will engage within groove 98 until shoulder 102 abuts vertical edge 104 of the projection.

At the lowermost portion of finger 88, it is provided with a rounded cam edge 106, terminating at a vertical edge 108 which leads away into an edge 110. When the closure gravitates to cover the opening, cam edge 106 will be positioned to, and will, ride up on cam surface 96 with which it will, at that time, be brought into association. Due to the construction of the latching mechanism, the location of cam edge 106 for cooperation with cam surface 96 is at all times assured. The finger will be pushed into its pocket until edge 108 has passed vertical edge 112 of the projection. The finger will now gravitate until its edge 110 abuts the projection, the closure being retained against return movement by engagement of edges 108 and 112 until the finger has been lifted to release this engagement.

For the purpose of lifting finger 88, it has secured to it, immediately adjacent edge 110, a shank 114. The shank extends upwardly through a slot 116 in plate 86 by which the shank is guided in its movement. The end of the slot acts as a stop for the finger in its vertical movement. At the outer end of the shank is applied a button 118 by means of which manipulation of the latching mechanism may be effected. It is to be noted that when an upwardly directed pressure is applied against the button to slide the finger upwardly within its recess, that same pressure, continuing its action in the same plane, will also effect rotation of the closure with relation to its pivot. In this connection, it is important that the movement of the finger is extremely limited, that except for its slight slip, it is substantially of the same character as a fixed button on the closure plate, and further that the movement of the finger must occur in a single plane. No awkwardness is introduced in the movement of the closure plate to open position, this being accomplished in a single, continuous, smooth movement of the finger substantially in a single direction.

Embodying certain features of the invention, the finger may, after riding up on and clearing cam surface 96, fall into an opening or recess in the projection to lock the closure plate against movement in any direction.

Therefore, when the latching mechanism is operative and is in engagement with the projection, the plate is restrained by the engagement of latching mechanism 82 and shoulder 102 with

projection 48 against pivoting movement in either direction, while the engagement of flange 78 within groove 98 prevents movement away from plate 32 of the closure if a force be applied against it in that direction.

Immediately adjacent boss 46, recess 50 may be formed in plate 32, this recess being contoured along arcuate lines substantially concentric with the boss. A knob 120 may be projected from the face of closure plate 52, in the same radial relationship to opening 56 as is recess 50 to boss 46. When the closure plate is in opening covering position, the knob will be housed within the recess. However, when the closure plate has been pivoted away from opening covering position, after suitable actuation of the latching mechanism, the knob will act as a stop, coming in contact with the shoulder formed by the rise 40 on plate 32. This stopping operation, in conjunction with the cooperation of shoulder 102 and projection 48, limits rotation of the closure in such manner that, at no time, can it assume a position in which gravity would not tend to move it to full opening covering position and to effect proper operation of the latching mechanism. The length of recess 50 may be made such that knob 120 will cooperate therewith in stopping the plate as does shoulder 102 and projection 48, or with the elimination of the shoulder.

Preferably immediately above recess 72 is another recess 122, formed with walls 124 converging inwardly from surface 70 to a slit 126 of very little width, from which walls 128 then diverge outwardly for a very short distance to face 130. The slit, by reason of converging walls 124 and diverging walls 128, permits one within the dwelling to view persons standing outside the door without first opening closure plate 52. If desired, a small leaf 132 may be pivoted to fall freely over slit 126. A stop may be provided for the leaf, or bearing portion 54 may function as such a stop.

In this manner, an article lending itself to compactness in structure and simplicity in its operation has been produced. The closure will resist any normal type of attack from the exterior and will not release upon such an attack unless destroyed.

Many other changes could be effected in the particular apparatus designed, and in the manner of use set forth, and in specific details thereof, without substantially departing from the invention defined in the claims, the specific description herein being merely to illustrate an operative embodiment carrying out the spirit of the invention.

What is claimed as new and useful is—

1. A wicket for a door to permit inspection of conditions on the side of the door obversely related to the observer without the necessity of opening the door, and for association at an opening through the door for that purpose provided, which comprises a frame for the opening, a closure for the opening pivoted upon the frame at the inner face thereof, the closure being so pivoted that it tends normally to gravitate to a position where it will cover the entire opening, the closure moving in a plane substantially parallel to the door upon which it is to be mounted, an abutment on the frame, the abutment being formed to receive and engage the closure when it reaches substantially the opening covering position, a projection from the closure, said projection, when the closure has gravitated to its opening covering position, being stopped against the

abutment, and a latch carried by the plate, the latch, when the closure is moved to opening covering position, riding vertically over the abutment beyond the receiving and engaging portion 5 of the abutment and assuming a position to engage against the abutment on the side removed from that with which the projection is to abut.

2. A wicket for a door to permit inspection of conditions on the side of the door obversely related to the observer without the necessity of opening the door, and for association at an opening through the door for that purpose provided, which comprises a frame for the opening, a closure for the opening pivoted upon the frame at 10 the inner face thereof, the closure being so pivoted that it tends normally to gravitate to a position where it covers the entire opening, the closure moving in a plane substantially parallel to the door upon which it is to be mounted, an abutment on the frame, the closure having a flange and the abutment having a kerf in substantially the same plane as the flange on the closure, the kerf receiving and engaging the flange when the closure reaches substantially the opening covering 15 position, a projection from the closure, said projection, when the closure has gravitated to its opening covering position, being stopped against the abutment, and a latch carried by the plate, the latch, when the closure is moved to opening covering position, riding vertically over the abutment outside the kerf and assuming a position to engage against the abutment on the side removed from that with which the projection is to abut.

3. A wicket for a door to permit inspection of conditions on the side of the door obversely related to the observer without the necessity of opening the door, and for association at an opening through the door for that purpose provided, which comprises a frame for the opening, a closure for the opening pivoted upon the frame at 35 the inner face thereof, the closure being so pivoted that it tends normally to gravitate to a position where it will cover the entire opening, the closure moving in a plane substantially parallel to the door upon which it is to be mounted, an abutment on the frame, the closure having a flange and the abutment being formed to receive and engage the flange when the closure reaches substantially the opening covering position, a portion of the flange being cut away to form a 40 projection, said projection, when the closure has gravitated to its opening covering position, being stopped against the abutment, and a latch carried at the lowermost portion along the vertical 45 diameter of the plate when in lowermost position, the latch being restricted to movement within a plane parallel to the plane of movement of the closure, the latch, when the closure is moved to opening covering position, riding over the abutment and assuming a position to engage 50 against the abutment on the side removed from that with which the projection is to abut.

4. A wicket for a door to permit inspection through an opening through the door of conditions on the side of the door obversely related to the observer without the necessity of opening the door, which comprises a frame for mounting at an opening through a door, a closure for the opening pivoted upon the frame at the inner face 65 thereof, the closure being so pivoted that it tends normally to gravitate to a position where it will cover the entire opening, the closure moving in a plane substantially parallel to the door upon which it is to be mounted, an abutment on the frame, the projection from the closure, said projec- 70

tion, when the closure has gravitated to its opening covering position, being stopped against the abutment, and a latch mounted for sliding movement only on the plate, the latch, when the closure is moved to opening covering position, riding vertically over the abutment and assuming a position to engage against the abutment on the side removed from that with which the projection is to abut. 5

5. A wicket for a door to permit inspection through an opening through the door of conditions on the side of the door obversely related to the observer without the necessity of opening the door, which comprises a frame for mounting at an opening through a door, a closure for the opening pivoted upon the frame at the inner face thereof, the closure being so pivoted that it tends normally to gravitate to a position where it will cover the entire opening, the closure moving in a plane substantially parallel to the door upon which it is to be mounted, an abutment on the frame, a projection from the closure, said projection, when the closure has gravitated to its opening covering position, being stopped against the abutment, a downwardly opening pocket in the plate, and a latch retained within and slidable into and out of the pocket, the latch, when the closure is moved to opening covering position, riding over the abutment and assuming a position to engage against the abutment on the side removed from that with which the projection is to abut. 10 15 20 25 30

6. A wicket for a door to permit inspection through an opening through the door of conditions on the side of the door obversely related to the observer without the necessity of opening the door, which comprises a frame for mounting at an opening through a door, a closure for the opening pivoted upon the frame at the inner face thereof, the closure being so pivoted that it tends 35 normally to gravitate to a position where it will cover the entire opening, the closure moving in a plane substantially parallel to the door upon which it is to be mounted, an abutment on the frame, a projection from the closure, said projection, when the closure has gravitated to its opening covering position, being stopped against the abutment, a shouldered recess in the plate, a plate covering the recess and resting upon the shoulder, a latch having only sliding movement 40 within the recess and below the cover plate, and a member securing the cover plate in position over the recess and limiting downward movement of the latch, the latch, when the closure is moved to opening covering position, riding over the 45 abutment and assuming a position to engage against the abutment on the side removed from that against which the projection is to abut. 50 55 60

7. A wicket for a door to permit inspection of conditions on the side of the door obversely related to the observer without the necessity of opening the door, and for association at an opening through the door for that purpose provided, which comprises a frame for the opening, a closure for the opening pivoted upon the frame at 65 the inner face thereof, the closure being so pivoted that it tends normally to gravitate to a position where it will cover the entire opening, the closure moving in a plane substantially parallel to the door upon which it is to be mounted, an 70 abutment on the frame, the closure having a flange and the abutment having a kerf in substantially the same plane as the flange on the closure, the kerf receiving and engaging the flange when the closure reaches substantially the 75

opening covering position, a portion of the flange being cut away to form a projection, said projection, when the closure has gravitated to its opening covering position, being stopped against the 5 abutment, a shouldered recess in the plate, a plate covering the recess and resting upon the shoulder, a latch sliding within the recess and below the cover plate, means securing the cover plate in position over the recess and limiting 10 downward movement of the latch, the latch, when the closure is moved to opening covering position, riding over the abutment beyond the kerf and assuming a position to engage against the abutment on the side removed from that 15 against which the projection is to abut, a slot in the cover plate, and a button secured to the latch and extending upwardly therefrom through the slot.

8. A wicket for a door to permit inspection 20 through an opening through the door of conditions on the side of the door obversely related to the observer without the necessity of opening the door, which comprises a frame secured at an opening through the door, the frame including 25 an embossed surface, a closure for the opening pivoted upon the frame at the inner face thereof and mounted to slide over the embossed surface, a knob formed on the closure and extending toward the frame immediately adjacent the point 30 of pivoting of the closure, a slot in the embossed surface for receiving the knob at one limit of movement of the closure, the knob being positioned to engage against the edge of the embossed surface at the other limit of movement 35 of the closure, the closure being so pivoted that it tends normally to gravitate to a position where it will cover the entire opening, the closure moving in a plane substantially parallel to the door upon which it is to be mounted, an abutment 40 on the frame, a projection from the closure, said projection, when the closure has gravitated to its opening covering position, being stopped against the abutment, and a latch carried by the plate, the latch, when the closure is moved to opening 45 covering position, riding over the abutment and assuming a position to engage against the abutment on the side removed from that with which the projection is to abut and then being wholly outside the abutment.

50 9. A wicket for a door to permit inspection through an opening through a door of conditions on the side of the door obversely related to the observer without the necessity of opening the door, which comprises a frame for the opening, the frame including an embossed surface, a closure for the opening pivoted upon the frame at the inner face thereof and mounted to slide over the embossed surface, a knob formed on the closure and extending toward the frame immediately adjacent the point of pivoting of the closure, a slot in the embossed surface for receiving the knob when the closure moves to opening covering position, the knob being positioned to engage against the edge of the embossed surface 55 to limit uncovering movement of the closure, the pivot for the closure being just off the vertical line through the center of gravity of the closure so that the closure tends normally to gravitate to a position where it will cover the entire opening, the closure moving in a plane substantially parallel to the door upon which it is to be mounted, an abutment on the frame, a projection from the closure, said projection, when the closure has 60 gravitated to its opening covering position, being stopped against the abutment, and a latch having only sliding motion within the other recess, the latch, when the closure is moved to opening covering position, riding over the abutment and assuming a position to engage against the abutment on the side removed from that with which the projection is to abut.

65 10. A wicket for a door to permit inspection through an opening through a door of conditions on the side of the door obversely related to the observer without the necessity of opening the door, which comprises a frame for the opening, the frame including an embossed surface, a closure for the opening pivoted upon the frame at the inner face thereof and mounted to slide over the embossed surface, a knob formed on the closure and extending toward the frame immediately adjacent the point of pivoting of the closure, a slot in the embossed surface for receiving the knob when the closure moves to opening covering position, the knob being positioned to engage against the edge of the embossed surface to limit uncovering movement of the closure, the pivot for the closure being just off the vertical line through the center gravity of the closure so that the closure tends normally to gravitate to a position where it will cover the entire opening, the closure moving in a plane substantially parallel to the door upon which it is to be mounted, an abutment on the frame having a surface rising vertically, a projection from the closure, said 70 projection, when the closure has gravitated to its opening covering position, being stopped against the abutment, and a latch carried by the plate, the latch, when the closure is moved to opening covering position, riding over the vertically rising surface, and then assuming a position engaging against the abutment on the side removed from that with which the projection is to abut and then being wholly outside the abutment.

75 11. A wicket for a door to permit inspection through an opening through a door of conditions on the side of the door obversely related to the observer without the necessity of opening the door, which comprises a frame for the opening, a closure for the opening pivoted upon the frame at the inner face thereof, the outer face of the closure being visible through the opening and the frame at the outer face of the door, the closure being so pivoted that it tends normally to gravitate to a position where it will cover the entire opening, a pair of recesses in the faces of the closure, the respective recesses opening at the respective opposed faces of the closure and one of them being visible through the opening in the door and the frame, indicia carrying members seated in the last mentioned recess, the closure moving in a plane substantially parallel to the door upon which it is to be mounted, an abutment on the frame, a projection from the closure, said projection, when the closure has 80 gravitated to its opening covering position, being stopped against the abutment, and a latch having only sliding motion within the other recess, the latch, when the closure is moved to opening covering position, riding over the abutment and assuming a position to engage against the abutment on the side removed from that with which the projection is to abut.

85 12. A wicket for a door to permit inspection through an opening through a door of conditions on the side of the door obversely related to the observer without the necessity of opening the door, which comprises a frame secured at an opening through the door, a closure for the opening pivoted upon the frame at the inner face 90

thereof, the outer face of the closure being visible through the opening and the frame at the outer face of the door, the closure being so pivoted that it tends normally to gravitate to a position where 5 it covers the entire opening, the closure moving in a plane substantially parallel to the door upon which it is to be mounted, an abutment on the frame, a projection from the closure, said projection, when the closure has gravitated to its 10 opening covering position, being stopped against the abutment, a pair of recesses in the faces of the closure, one recess opening at one face and the other recess opening at the other face of the closure and one of them being visible through 15 the opening in the door and the frame, indicia carrying members seated in the last mentioned recess, the other recess being shouldered, a plate covering the other recess and resting upon the shoulder, a latch having sliding movement with- 20 in the other recess and below the cover plate, means securing the cover plate in position over the recess and limiting downward movement of the latch, the latch, when the closure is moved to opening covering position, riding over the 25 abutment and assuming a position to engage against the abutment on the side removed from that with which the projection is to abut, a slot in the cover plate, and a button secured to the latch and extending upwardly therefrom through 30 the slot.

13. A wicket for a door to permit inspection through an opening through the door of conditions on the side of the door obversely related to the observer without the necessity of opening 35 the door, which comprises a frame secured at an opening through the door, a closure for the opening pivoted upon the frame at the inner face thereof, the closure being so pivoted that it tends normally to gravitate to a position where it will 40 cover the entire opening, the closure moving in a plane substantially parallel to the door upon which it is to be mounted, an abutment on the frame, a projection from the closure, said projection, when the closure has gravitated to its 45 opening covering position, being stopped against the abutment, a shouldered recess in the plate, a plate covering the recess and resting upon the shoulder to form a slideway, a latch sliding within the slideway, means securing the cover plate 50 in position over the recess and limiting downward movement of the latch, the latch, when the closure is moved to opening covering position, riding over the abutment and assuming a position to engage against the abutment on the side removed from that with which the projection is to 55 abut, and a button secured to the latch and extending upwardly therefrom through the cover plate, the button being disposed at the lowest point of the closure when the closure is positioned 60 in full opening covering position.

14. A wicket for a door to permit inspection through an opening through the door of condi-

tions on the side of the door obversely related to the observer without the necessity of opening the door, which comprises a frame secured at an opening through the door, a closure for the opening pivoted upon the frame at the inner 5 face thereof, a pivot for the closure so that the closure tends normally to gravitate to a position where it will cover the entire opening, the closure moving in a plane substantially parallel to the door upon which it is to be mounted, a peep-hole 10 through the closure, a leaf pivoted upon the closure and tending gravitationally to assume a position covering the peep-hole, the leaf being stopped by the closure pivot in its movement to peep-hole uncovering position, and means on the 15 closure and the frame for latching the closure against any movement when the closure has gravitated to opening covering position.

15. In combination with a door, of means to permit guarded inspection through an opening 20 through the door of conditions on the side of the door obversely related to the observer without opening the door, which comprises a frame for the opening, means for securing the frame to the door, a closure for the opening pivoted upon 25 the frame at the inner face thereof, stops for limiting pivoting movement of the closure with relation to the opening, said stops operating to dispose the closure at all times in gravitationally unbalanced condition, and means associated with 30 one of the stops for latching the closure automatically in opening covering position, the closure, in opening covering position, covering and concealing the frame securing means.

16. A wicket for a door to permit inspection of 35 conditions on the side of the door obversely related to the observer without the necessity of opening the door, and for association at an opening through the door for that purpose provided, which comprises a frame for the opening, a closure for the opening mounted upon the frame at the inner face thereof, a pivot for the closure, the closure being so mounted on the pivot that it tends normally to gravitate to a position where it will cover the entire opening, the closure moving in a plane substantially parallel to the door upon which it is to be mounted, an abutment on the frame at the lowermost portion thereof and having a slot in the plane of movement of the closure to receive and engage the closure when 40 it reaches substantially opening-covering position; the pivot and the abutment slot cooperating, when the closure is in substantially opening-covering position, to prevent movement of the closure other than in said plane; and a latch carried 45 at the lowermost portion of the plate and providing the sole means for actuating the plate to open position, the latch engaging the frame wholly externally of said slot to restrain the closure against any movement, the latch having only 50 55 60 sliding movement.
